UNITED STATES PATENT OFFICE

CARL A. O. GRIP, OF NEWTONVILLE, MASSACHUSETTS, ASSIGNOR TO THE REECE
BUTTON HOLE MACHINE COMPANY, OF BOSTON, MASSACHUSETTS, A CORPORATE
ATION OF MAINE

BUTTONHOLE SEWING MACHINE

Application filed May 24, 1932. Serial No. 613,217.

This invention relates to buttonhole sewing machines and has for one of its objects to provide a novel means for pulling off a length of under thread at the end of the sewing operation preparatory to cutting the under thread and stay cord.

Another object of the invention is to provide improved means for guiding the reciprocating movements of the under thread mechanism which is mounted on the turret.

In order to give an understanding of the invention I have illustrated in the drawings a selected embodiment thereof which will now be described after which the novel features will be pointed out in the appended claims.

Fig. 1 is a side view of a portion of a buttonhole sewing machine embodying the invention;

Figs. 2 and 3 are views of the turret and the under thread mechanism carried thereby;

Fig. 4 is a fragmentary sectional view showing the operation of the under thread pull-off;

Fig. 5 is a sectional view of the under thread pull-off arm taken on substantially the line 7—7, Fig. 3;

Fig. 6 is a section on the line 8—8, Fig. 5;

Fig. 7 is a section on the line 1—1, Fig. 2 looking upwardly in said figure;

Fig. 8 is a fragmentary view illustrating the operation of the under thread pull-off arm;

Fig. 9 is a fragmentary view showing a slightly different way of mounting the pull-off arm than that shown in Figs. 5 and 6;

Fig. 10 is a section on the line 10—10, Fig. 9 but illustrating the pull-off arm in elevation.

The buttonhole sewing machine herein illustrated has the usual work-holding means which is mounted on the bed plate 1 and the usual stitch-forming mechanism which is carried by a stitch frame indicated generally at 2. The stitch frame and the bed plate have a movement relative to each other during the sewing on the buttonhole and also a further relative movement to carry the parts from stitching to buttonhole cutting

position as usual in buttonhole sewing machines of this type.

The work-holding means comprises work clamps 3 by which the work 4 is clamped against the mats 5 which are carried by the clamp plates 6, the latter being removably mounted on the bed plate 1 as usual.

The stitch-forming mechanism comprises the usual needle 7 carried by a needle bar 8 which is mounted for reciprocation in the stitch frame 2, and also under thread mechanism which is carried by the turret 9 that is rotatively mounted in the portion 10 of the stitch frame on the opposite side of the work from the needle.

The turret 9 carries the usual throat plate or "button" 11 which is provided with the sewing opening 12 through which the needle 7 operates.

The under thread mechanism is of the type which comprises the loopers 13 and the loop spreaders 14, said loopers and spreaders being carried on the oscillating looper-carrying block 15 which is mounted to oscillate upon a stud 16. The means for oscillating the looper-carrying block 15 is similar to that usually employed in buttonhole sewing machines of this type. Said block is connected by a link 17 to a hollow spindle 18 which reciprocates vertically in the turret 9. Said spindle is actuated by a lever 19 pivoted to the portion 10 of the frame at 20 and connected by a link 21 to a suitably actuated lever which gives the lever 19 its required oscillating movement.

The loop spreaders are actuated as usual by means of a spreader wedge indicated at 22 which is also mounted for oscillation on the stud 16 and is connected by a link 23 to a spindle 24 which extends axially through the spindle 18 and which is actuated by a lever 25 pivoted at 26 to the portion 10 of the stitch frame, said lever 25 being connected by a link 27 to a suitably actuated lever.

It will be understood by those familiar with buttonhole sewing machines that, during the sewing of the buttonhole, the stitch frame 2 and the work-holding means will have a relative feeding movement and when the sewing on the buttonhole has been com-

pleted and the stitch-forming mechanism has come to rest with the needle retracted as shown in Fig. 1, said stitch frame and work-holding means will have a further relative 5 movement to carry the parts from stitching to buttonhole-cutting position, the button-hole-cutting position being indicated by the dotted lines in Fig. 1. During this further movement the under thread 28 which is led 10 to the work from the threaded looper through the sewing opening 12 of the throat plate 11, and the stay cord 29 which is also led to the work through the sewing opening 12, will be drawn out through the sewing opening as 15 illustrated in Fig. 4 so that there will be a length of the thread and the stay cord extending from the stitched buttonhole 30 to the throat plate 11 and lying on the opposite side of the work from the needle.

20 One feature of the invention relates to a novel pull-off device for acting on the length of under thread between the throat plate and the work to pull off a length of under thread from the source of supply sufficient to enable the first stitch on the next buttonhole to be properly formed.

25 The under thread pull-off is in some respects similar to that shown in co-pending application of Joseph Pikul, Serial No. 525,376, filed March 26, 1931. As illustrated in Figs. 4 and 5 it is mounted on the turret and comprises a pull-off arm 31 pivotally mounted on the stud 16 and provided at its upper end with a pull-off hook 32 adapted 30 during the operative swinging movement of the arm 31 toward the left in Fig. 3 to engage the under thread 28 between the throat plate 11 and the work and thereby pull a length of under thread through the throat 35 plate from the source of supply, it being understood that the tension on the under thread will be released at this time by mechanism usually employed for that purpose thereby to allow the under thread to be freely drawn 40 from the source of supply. The amount of under thread which is thus pulled through the throat plate is sufficient so that when the under thread has been cut close to the work by any suitable thread-cutting device there 45 will be projecting from the throat plate a sufficient length of under thread properly to form the first stitch on the next buttonhole.

50 This pull-off arm 31 is normally held in its inoperative position by a spring 85 which is connected at one end to said arm and at the other end to an anchorage 96 carried by the turret 9. Said pull-off arm 31 is shown in Figs. 5 and 6 as provided at its lower end with a split hub 33 which encircles and is 55 clamped to a sleeve 34 that is mounted for turning movement on an extension 35 of the stud 16. The split hub 33 is clamped to the sleeve 34 by means of a clamping screw 36. The sleeve 34 is provided with a slot 37 in 60 which is received a stop pin 38 carried by the

stud extension 35, said stop pin and slot limiting the extent of the spring-impelled return turning movement of the sleeve about the stud and consequently stopping the arm 31 in its proper inoperative position.

70 The throat plate 11 herein illustrated is constructed similar to that shown in the machine illustrated in the above-mentioned co-pending application Serial No. 525,376, in that it has a slot 39 into which the under thread 28 is received when the parts have been moved into buttonhole-cutting position as shown in Fig. 4, the cord 29 at such time resting on top of the throat plate and thus being above the portion of the under thread which extends from the throat plate to the work. When the pull-off arm is given its operative movement from the full to the dotted line position Fig. 8 the hook 32 engages the under thread 28 but does not engage the cord 29 so that the pull-off arm acts only on the under thread.

75 The pull-off arm is given its operative movement by the reverse rotative movement of the turret 9 which occurs after the sewing of the buttonhole has been completed. Those who are familiar with button hole sewing machines will understand that in sewing around the eye end of the buttonhole the turret will have a half rotation and that after the sewing on the buttonhole has been completed and the stitch-forming mechanism has come to rest and either during or directly after the movement by which the stitch frame and work-holding means are carried into buttonhole-cutting position the turret will be given a reverse rotative movement to bring it back into initial position ready for the stitching on the next buttonhole.

80 The pull-off arm 31 is of the type which is actuated by this reverse rotative movement. For this purpose the hub 33 of said pull-off arm has adjustably mounted thereon a depending tail 40 which extends down through the upper ring 41 of the turret and is 85 adapted to engage a dog 42 carried on the under side of the bearing portion 43 of the stitch frame in which the turret is mounted. This dog is shown as pivotally mounted on a stud 44 carried by the portion 43 of the stitch frame and is acted on by a spring 45 which normally holds it in its operative position shown in Fig. 7 in which it rests against a stop pin 46. When in this position the end 47 thereof is in the path of movement of the laterally-bent end 48 of the tail 40. At the time that the stitch-forming mechanism comes to rest the turret will be so positioned in its bearing that the laterally-extending end 48 of the tail 40 will be in close proximity to the end 47 of the dog 42 and as the turret is given its reverse rotative movement in the direction of the arrow in Fig. 7 the end 48 of the tail 40 will strike the end 47 of the dog 42 so that during the further rotative movement 90

130

the pull-off arm 31 will be swung about its pivot as shown in dotted lines Fig. 8 thereby causing the pull-off hook 32 to engage the under thread and pull a sufficient length therefrom from the source of supply through the throat plate.

As the turret continues its rotative movement the end 48 of the tail 40 will wipe over the end 47 of the dog 42 and the spring 85 will then return the pull-off arm to its normal position, which position is determined by the engagement of the pin 38 with one end of the slot 37 as previously mentioned.

One feature of the present invention relates to means by which the amount of thread which is pulled off may be adjusted according to the requirement of use. This is accomplished by providing means whereby the tail 40 may be adjusted vertically with relation to the hub 33.

As shown in Fig. 6 the tail 40 is made separately from the hub 33, the latter having a flat face 49 to which the upper end of the tail 40 is adjustably secured. Said upper end is shown as having a slot 50 therein through which the clamping screw 36 extends, said screw performing the double function of clamping the hub 33 to the sleeve 34 and also clamping the tail 40 to the hub. 52 is a stud pin fast to the hub 33 and occupying the slot below the clamping screw 36. By loosening the screw 36 the tail 40 can be adjusted vertically, the screw 36 when tightened serving to clamp the tail in its adjusted position. The pin 52 serves to hold the tail firmly in its adjusted position and prevent possible rotation about the clamping screw 36.

The extent of the swinging movement of the pull-off arm and consequently the amount of under thread which is pulled off depends upon the relative position in a vertical direction of the end 48 of the tail and the end 47 of the dog, because during the turning movement of the turret the end 48 of the tail first engages the end 47 of the dog and then as the tail swings said end 48 wipes over the end 47 of the dog. If the adjustment is such that the lower edge of the end 48 just barely engages the end 47 of the dog then the tail will wipe over the dog after the arm 31 has had a slight swinging movement while if the tail 40 is adjusted downwardly then said tail and the arm 31 will have a greater swinging movement before the end 48 wipes over the end 47 of the dog. By this simple means the action of the pull-off arm can be regulated so as to pull off the desired amount of under thread at the end of each buttonhole.

58 indicates a stay cord guide through which the stay cord is guided to the throat plate, said guide being of the type which will permit the stay cord to be fed forwardly but will prevent retrograde movement thereof.

In the construction shown in Figs. 5 and 6 the hub 33 of the pull-off arm 31 is clamped to the sleeve 34 which is retained on the head

35 of the stud 16 by the engagement of the pin 38 in the slot 37 of the sleeve.

In Figs. 9 and 10 I have shown a slightly different construction. In this embodiment the pull-off arm is indicated at 31a and it is shown as detachably secured to a hub member 33a that is rotatively mounted on the head 35a of the stud 16a which forms the pivot for the looper-carrying block 15 and which corresponds to the stud 16 in Figs. 5 75 and 6.

The pull-off arm 31a is shown as adjustably clamped to an arm 61 extending from the hub 33a by means of a screw 62, said pull-off arm having a slot 63 which permits the pull-off arm to be vertically adjusted.

The hub 33a is mounted on the head 35a of the stud 16a so as to freely rotate and it is retained on said head by a retaining fin 64 which passes through a slot 65 in the hub 33a 85 and enters an annular groove 66 formed in the head 35a. This locking fin 64 is shown as carried by a resilient finger 68 which is secured to the hub 33a by a suitable screw 67. The resiliency of the finger 68 permits the fin 64 to be withdrawn from the groove 66 thereby permitting the hub 33a to be slipped off from the head 35a in case it is desired to remove the hub 33a and pull-off finger.

I claim: 95

1. In a buttonhole sewing machine, the combination with a stitch frame, of a turret rotatively mounted thereon, stitch-forming mechanism including loopers pivotally mounted on the turret to oscillate about a common axis, a thread pull-off arm pivoted co-axially with the loopers and adapted to engage the under thread to pull a length thereof from the source of supply, and means to actuate the pull-off arm after the sewing operation is completed.

2. In a buttonhole sewing machine, the combination with work-holding means, of a stitch frame, stitch-forming mechanism carried by the stitch frame and including oscillating loopers operating on the opposite side of the work from the needle, a turret on which said loopers are pivotally mounted, an under thread pull-off arm pivoted on the turret co-axial with the loopers, said turret having a rotary movement after the stitching operation is completed, and means rendered operative by such rotary movement to actuate the pull-off arm.

3. In a buttonhole sewing machine, the combination with a stitch frame, of a rotary turret mounted thereon, stitch-forming mechanism including loopers mounted on the turret for oscillating movement, an under thread pull-off arm pivoted co-axially with the loopers said turret having a reverse rotative movement after the completion of the stitching of the buttonhole, a tail depending from the pull-off arm and a dog carried by the stitch frame adapted to engage said tail during such 130

- reverse rotary movement, thereby to actuate the pull-off arm.
4. In a buttonhole sewing machine, the combination with a stitch frame, of a rotary ⁷⁰ turret mounted thereon, stitch-forming mechanism including loopers mounted on the turret for oscillating movement, an under thread pull-off arm pivoted co-axially with the loopers, said turret having a ⁷⁵ reverse rotative movement after the completion of the stitching of the buttonhole, a dog carried by the stitch frame and a tail depending from the pull-off arm and adapted to engage and wipe over the dog during the ⁸⁰ reverse rotative movement of the turret thereby to actuate the pull-off arm.
5. In a buttonhole sewing machine, the combination with a stitch frame, of a rotary ⁸⁵ turret mounted thereon, stitch-forming mechanism including loopers mounted on the turret for oscillating movement, an under thread pull-off arm pivoted co-axially with the loopers, said turret having a ⁹⁰ reverse rotative movement after the completion of the stitching of the buttonhole, a dog carried by the stitch frame and a tail depending from the pull-off arm and adapted to engage and wipe over the dog during the ⁹⁵ reverse rotative movement of the turret thereby to actuate the pull-off arm, said tail being ¹⁰⁰ adjustable vertically thereby to provide for a variation in the amplitude of swinging movement of the pull-off arm and a corresponding variation in the amount of thread drawn off.
6. In a buttonhole sewing machine, the combination with a stitch frame, of a turret ¹⁰⁵ rotatively mounted thereon, said turret having a throat plate, stitch-forming mechanism including oscillating loopers pivotally mounted on the turret, an under thread pull-off arm pivoted on the turret co-axially with the loopers and adapted to engage the under thread between the throat plate and the work, ¹¹⁰ said turret having a reverse rotary motion at the completion of each buttonhole, and means rendered operative by said reverse rotation to actuate the pull-off arm.
7. In a buttonhole sewing machine, the combination with a stitch frame, of a turret ¹¹⁵ rotatively mounted thereon, said turret having a throat plate, stitch-forming mechanism including oscillating loopers pivotally mounted on the turret, an under thread pull-off arm pivoted on the turret co-axially with the loopers and adapted to engage the under thread between the throat plate and the work, said turret having a reverse rotary motion at the completion of each buttonhole, ¹²⁰ means rendered operative by said reverse rotation to actuate the pull-off arm, and means for varying the amplitude of the pulling-off movement of the pull-off arm.
8. In a buttonhole sewing machine, the combination with a stitch frame, of a turret ¹²⁵
- rotatively mounted thereon and having a reverse rotation at the end of each buttonhole, stitch-forming mechanism including a looper-carrying block and loopers pivotally mounted on the turret, a stud on which said block oscillates, said stud having an extension, a thread pull-off arm pivotally mounted on the stud extension and adapted to engage the under thread to pull a length from the source of supply, and means to actuate the pull-off arm by the reverse rotary movement of the turret.
9. In a buttonhole sewing machine, the combination with a stitch frame, of a turret ¹³⁰ rotatively mounted thereon, stitch-forming mechanism including a looper-carrying block and loopers pivotally mounted on the turret, a stud on which said block oscillates, said stud having an extension provided with an annular groove, a thread pull-off member pivotally mounted on the stud extension and adapted to engage the under thread to pull a length from the source of supply and means to actuate the pull-off member, and a spring-pressed locking fin carried by said member and adapted to engage in said groove to retain the member on the stud.
- In testimony whereof, I have signed my name to this specification.
- CARL A. O. GRIP. ⁹⁵
